(57) **CLAIM**

The ornamental design for a berm with smooth transition groove, as shown and described.

DESCRIPTION

FIG. 1 is a front view of a berm with smooth transition groove showing our new design in accordance with a first embodiment, the rear view being identical thereto; FIG. 2 is a left side view thereof, the right side view being identical thereto;

FIG. 3 is a top view thereof;

FIG. 4 is a bottom view thereof;

FIG. 5 is a top, front, and right perspective view thereof;

FIG. 6 is a top, front, and right perspective exploded view thereof in its intended environment; and,

FIG. 7 is a top, front, and left perspective view thereof in its intended environment.

The broken lines in the drawings represent environmental subject matter only and form no part of the claimed design. The dot-dash lines immediately adjacent the shaded areas in FIGS. 1, 3, and 5-7 represent a claim boundary and form no part of the claimed design. The berm with smooth transition groove is shown with a symbolic break in its length in FIGS. 2 and 3. The appearance of any portion of the berm with smooth transition groove between the break lines form no part of the claimed design.

1 Claim, 7 Drawing Sheets
